UNITED STATES PATENT OFFICE

2,496,205

FOLDABLE AUXILIARY BABY SEAT

Charles Grieb, Flushing, N. Y.

Application June 25, 1947, Serial No. 756,980

2 Claims. (Cl. 155—131)

1

This invention relates generally to a combination child's chair, but most specifically to a child's chair adaptable for application to a normal sitting chair.

The main object of the invention resides in the provision of a child's or nursery chair capable of being folded in a compact form to expedite portability and capable of being used as a child's chair per se or in conjunction with the conventional sitting chair.

A further object of the invention resides in the provision of a foldable child's chair having novel and simple construction and which can be manufactured economically and which is efficient and practical in use.

These objects and other ends and advantages of the invention will hereinafter appear in the progress of the disclosure and as pointed out in the appended claims.

Accompanying this specification are drawings showing a preferred form of the invention wherein:

Figure 1 is a view in perspective showing a foldable child's chair as applied to and in operating condition with a conventional sitting chair, the latter being shown in phantom.

Figure 2 is a front view in perspective of Figure 1.

Figure 3 is a front view in elevation of the chair per se when in folded position.

Figure 4 is a fragmentary sectional view of Figure 2 along the broken plane 4—4.

In accordance with the invention and the preferred form shown in the drawings, numeral 10 shown in phantom indicates a conventional sitting chair to which the child's chair is applicable for conversion to a high-chair.

The foldable chair adapted to rest either on the floor or on the seat 11 of chair 10 is provided with a flat body member 12 having a pair of notches along each of the longitudinal edges adjacent the ends; each pair of said notches being indicated by numerals 13 and 13a respectively. Each of the transverse edges of body member 12 is rounded as indicated by numerals 14 and 14a respectively.

Each pair of notches 13 and 13a is adapted to serve as the seating means for pivoted brackets which engage both the side walls and the supporting means for the child's chair. As shown in the drawings the brackets generally indicated by numerals 15 and 15a and adapted to be pivotally seated in the notches 13 and 13a along the front longitudinal edge of body member 12 are provided with pivotal plate portions and spaced and

2

oppositely disposed channel portions. The upwardly disposed channel portion of each bracket is intended to engage an edge of a side wall while the downwardly disposed channel portion is adapted to engage an edge of the supporting means for the child's chair. Thus the bracket 15 has a plate portion 16 of a width substantially equal to the body thickness of body member 12. The plate 16 has a thickness equal to that of notch 13 and is secured to one end of a transverse dowel 17 within a bore 18 in body member 12 by means of a screw 19 penetrating the plate 16 and engaging a bushing 20 within the end of the dowel 17. Sufficient clearance is provided between the dowel 17 and the bore 18 to permit rotation of dowel 17 with the rotary movement of plate 16.

At the inner end of plate 16 is an upwardly extending member 21 disposed above the upper face of body member 12 to receive the lower part of the front edge of the inner side wall 22, said member 21 being in the form of a channel. At the outer end of plate 16 is a downwardly extending channel 23 disposed below the underface of body member 12 to engage the front edge of the inner end front leg or supporting member 24. The channels 21 and 23 are permanently secured to the front edges of side wall 22 and of leg 24 by means of screws or nails 25.

The inner notch 13 along the rear longitudinal edge carries a similar type of bracket with the upper and lower channel members facing 25 and 23 and engaging the rear edges of the inner side wall 22 and of the rear inner leg 24a, said bracket having a bracket plate which is engageable with the opposite end of dowel 17. The legs 24 and 24a as shown are integral with a cross piece 25a.

The outer front bracket 15a is provided with a plate member 26 in notch 13a and is similarly secured to a dowel within a transverse bore adjacent the outer end of body member 12. Plate 26 at the outer end is provided with an upwardly projecting channel 27 disposed above the face of body member 12 to engage the lower end of the front edge of the outer side wall 28. The inner end of plate 26 is provided with a downwardly projecting channel 29 which is adapted to engage the edge of the front outer leg 30. The rear outer bracket similarly secured to the other end of the dowel is identical to bracket 15a except that the channels thereof are oppositely disposed.

As shown, side members 22 and 26 are provided with top edge rails 31 and 32 respectively beneath which are longitudinal slots 33 and 34 to effect grasping rails.

The supporting means are shown in the form of cross pieces held between each pair of transversely disposed brackets and disposed beneath the undersurface of body member 12, the ends of the cross pieces being elongated to furnish the front inner and outer legs 24 and 30 and the rear corresponding legs exemplified by the rear outer leg 24a. The lower edges of the side walls 22 and 26 are disposed along the upper face of body member 12, and the upper edges of the cross pieces as 25a are disposed along the underface of said body member.

For securing the child's chair to a conventional sitting chair the outer faces of the cross pieces of the supporting legs are provided with securing bands 34a and 35 which are adapted to pass under the seat 11 to be secured together by means of a buckle 36. In this secured position means are provided to prevent the inward folding of the side walls 22 and 28 shown in the form of a latch arm 37 secured to the inner face of the supporting cross piece 25 and an eyelet 38 secured to the inner face of the opposite cross piece. Upon removal of the bands 34a and 35 from seat 11 and upon unlatching latch arm 37 from eyelet 38 the side walls 22 and 28 are capable of folding toward each other along the upper face of body member 12 while the supporting legs and cross pieces fold oppositely and project from the underface of body member 12 all as 30 best shown in Figure 3.

The child's chair as described is capable of functioning as a child's stool without cooperating with the conventional chair. In this event latch 37 should be engaged with eyelet 38 to maintain the side walls and the supporting means in vertical position.

I wish it understood that minor changes and variations in the integration, location, material

and size of parts of the invention all may be resorted to without departing from the spirit of the invention and the scope of the appended claims.

5 I claim:

1. In a foldable child's chair, a seating member provided with notches adjacent the ends of the longitudinal edges thereof, a pair of side members and a pair of lateral supports, brackets each of which is pivotally secured in a notch of the seating member, each of the side members and corresponding supports being affixed to the transversely aligned brackets whereby the side members and the lateral supports are foldable about the supporting member.

10 2. In a foldable child's chair, a seating member having notches adjacent the ends of the longitudinal edges thereof, a pair of dowels penetrating and rotatable in the seating member and terminating in the transversely aligned notches, a pair of side members and a pair of lateral supports, pairs of end brackets mounted within the notches and secured to the dowel terminals and to each pair of which a side member and corresponding support is secured, means to maintain the brackets in fixed position for operative use of the chair.

CHARLES GRIEB.
